UNITED STATES PATENT OFFICE.

JOHN LEVEY, OF RIVERSIDE, ILLINOIS, ASSIGNOR TO NATIONAL MACHINE WORKS,
OF CHICAGO, ILLINOIS, A CORPORATION OF ILLINOIS.

VALVE FOR GAS-GENERATORS.

1,363,047.

Specification of Letters Patent. Patented Dec. 21, 1920.

Application filed December 10, 1919. Serial No. 343,972.

To all whom it may concern:

Be it known that I, JOHN LEVEY, a citizen of the United States, residing at Riverside, in the county of Cook and State of Illinois, have invented a new and useful Improvement in Valves for Gas-Generators, of which the following is a specification.

My invention relates to valves, more especially for gas generators, of the general type shown in United States Letters Patent No. 825,064 granted to me on July 3, 1906, and involving a valve and a superposed flue section connected together for simultaneous movement by a lifting force applied to the top of the flue section. It has been found in practice that where the valves are relatively large structures, the operation thereof as stated sometimes results in the permanent distortion of the movable flue section to such a degree that it is impaired for properly performing its function. Furthermore, as these structures have been hitherto provided, considerable difficulty is presented to the ready inspection of the movable flue section and its repair, removal, replacement or substitution.

My primary objects, generally stated, are to provide a construction of valve structure of the general type referred to which may be provided in large sizes and be readily actuated without danger of distorting the movable flue section, and the internal parts of which may be rendered quickly accessible for inspection or repair or removal for substitution.

Referring to the accompanying drawings:—Figure 1 is a vertical, sectional view of apparatus constructed in accordance with my invention, the section being taken at the line 1—1 on Fig. 4 and viewed in the direction of the arrows. Fig. 2 is a similar view of the lower end of the movable flue section and the upper end of the valve, showing these parts in disassembled relation. Fig. 3 is an enlarged, broken, section taken at the line 3 on Fig. 1 and viewed in the direction of the arrows. Fig. 4 is a section taken at the line 4—4 on Fig. 1 and viewed in the direction of the arrows, this view showing the valve and movable flue section in one position. Fig. 5 is a view like Fig. 4, showing the valve and movable flue section raised into another position. Fig. 6 is an edge view of the valve structure; and Fig.

7, a section taken at the line 7 on Fig. 4 and viewed in the direction of the arrows.

Inasmuch as I have devised my improvements for use more particularly in apparatus for manufacturing water gas, I have illustrated and will describe it in this connection.

In the arrangement shown, a valve casing is represented at 8 providing an upper inlet 9 which connects directly with the generator or retort (not shown), a lower inlet 10 connected with the generator below the fire grate thereof, and a common outlet 11 leading to the carbureter (not shown). The parts 9 and 11 form an interrupted passageway, and as this passageway is in the present instance designed to lead directly from the upper part of the generator into the carbureter, these parts are lined with refractory material represented at 12 and 13. The opening 10 may or may not be so lined. As herein shown, it is not provided with a lining.

The passageway from the inlet 9 to the outlet 11 is formed by a movable flue section 14, shown as of metal, the aperture therein forming the flue, being also preferably provided with a fire-proof lining 15 which, together with the fire-proofing in the parts 9 and 11, forms a continuous fire-proof passageway for the gases or the like, affording complete protection to the more or less destructible parts of the valve apparatus.

In the particular arrangement shown, the movable flue section 14 is in the form of an annulus provided at opposite sides with outwardly extending lugs 16 presenting beveled faces 17 adapted to engage the peripheries of rollers 18 journaled on stub shafts 19 mounted in opposite side walls of the valve casing 8, these rollers being so located that when the movable flue section 14 is in the position represented in Figs. 1 and 4, namely wherein it forms a continuation of the passageway through the flue sections 9 and 11, this flue section, by reason of the wedging action of the lugs 16 against the rollers 18, will be forced at one end, its right-hand end in Fig. 4, into rigid contact with the adjacent end of the flue passage 9 so that a gas-tight joint will be produced therebetween. The vertically movable flue section 14 is superposed on, and supported by, the valve proper 20 of the apparatus, this

valve being in the form of a circular disk operating when in the position shown in Figs. 1 and 4 to close the inlet 10 to the outlet 11, and when raised to the position shown in Fig. 5, to close the inlet 9 to the outlet 11 and permit communication between the latter and the inlet 10. The flue section 14 is provided with a depending web 21 provided at its opposite sides with pairs of lugs 22 spaced apart lengthwise of the web, at which web it rests upon the bottom of a socket 23 provided on the upper end of the valve proper 20, this socket containing pairs of inwardly projecting lugs 24 spaced apart lengthwise of the socket a distance slightly greater than the length of the lugs 22, the lugs 22 and 24 being of substantially the same length, the arrangement of the parts being such that when the movable flue section 14 and the valve 20 are vertically aligned as shown in Fig. 1, the lugs 22 will extend immediately below the lugs 24 and thus be in interlocked relation therewith.

The simultaneous shifting of the movable flue section 14 and the valve 20 is accomplished through the medium of a lifting force applied directly to the valve 20, the means shown for this purpose comprising a lever 25 formed of a pair of parallel members 26 secured to the ends of a shaft 27 and carrying at their outer end counterweights 28, the shaft 27 being journaled in an extension 29 of the casing 8 and rigidly carrying an arm 30 which is pivotally connected, through the medium of a pin 31, with the lower end of a link 32, the upper end of this link being pivotally connected by a pin 33 with the valve 20, the counterweighting portion of the lever mechanism 40 being such that, by preference, it will not accurately counter-balance the weight of the movable flue section and valve, but will substantially counter-balance it, but under no condition of the structure will it operate to raise the valve and movable flue section.

The valve 20 is provided on the face thereof opposite that at which it closes against the seat controlling the inlet 10, with a lug 34 presenting a wedge surface 35 adapted 50 to coöperate with a roller 36 journaled on a shaft secured to a wall of the valve casing 8, these parts coöoperating to cause the valve 20 to closely fit against the seat referred to and produce a gas-tight joint for closing 55 the inlet 10 in the position of the parts represented in Figs. 1 and 4.

It may be stated that when the parts of the apparatus assume the positions shown in Figs. 1 and 4, a direct passageway for the gases is provided through the flue sections 12, 14 and 13, the inlet 10 being effectually sealed. When the valve 20 and movable flue section 14 are raised in the valve casing 8 by pushing down on the outer end of the lever 25 to raise these parts to the position

shown in Fig. 5, the flue sections 12 and 13 are out of communication, and the gases, as shown by the arrows in Fig. 5, pass upwardly through the inlet 10 and out through the outlet 11. In the movement of the parts 70 to the position shown in Fig. 5 as described, the wedge surfaces 38 of the lugs 39 on the valve 20 engage the rollers 18 and through such engagement force the valve 20 into tight-joint-forming condition relative to the 75 inlet 9 as shown in Fig. 5.

The upper end or hood portion represented at 40 of the valve casing 8 is connected with the portion which it superposes by any suitable releasable means, as for example the bolts shown at 41, for the purpose of permitting the movable flue section 14 to be inspected and if desired removed, the lugs 16 of the movable flue section 14 in the raised position of these internal moving parts, as shown in Fig. 5, being above the joint between the section 40 and the portion of the casing on which it is supported, and the parts forming the connection between the valve and movable flue section 90 as hereinbefore explained, are so proportioned that the movable flue section may be shifted on the valve 20 in a direction lengthwise of the said connection to a position in which the lugs 22 and 24 are out of interlocking position, thereby permitting the flue section 14 to be lifted out of the valve casing for any desired purpose, as for example repair or substitution.

It will be understood from the foregoing 100 that inasmuch as the movable flue section 14 does not at any time support the weight of the valve, it may be made of relatively light weight without danger of distortion. Furthermore, the movable flue section 14 105 may be readily removed from the valve casing as stated, it being noted that the structure is free of overhead parts required to be moved before the flue section is withdrawable. This is of particular advantage in 110 a gas-making apparatus, inasmuch as the movable flue section may be inspected, removed from the valve casing and replaced or one substituted therefor, in the same length of time required for the cleaning of 115 the fires.

While I have illustrated and described a particular construction embodying my invention, I do not wish to be understood as intending to limit it thereto, as the same 120 may be variously modified and altered without departing from the spirit of my invention.

What I claim as new and desire to secure by Letters Patent is:

1. In valve apparatus, the combination 125 of a casing having an inlet port and an outlet, a movable flue section forming a passageway between the inlet and outlet, a valve associated with said movable flue sec- 130

tion and adapted to be moved to a position in which it is interposed between said inlet and said outlet when said flue section is removed from its position between said inlet and outlet, and means for moving said flue section and valve together constructed and arranged to permit said movable flue section to be removed from the casing without removing said means.

10 2. In valve apparatus, the combination of a casing having an inlet port and an outlet, a movable flue section forming a passageway between the inlet and outlet, and a movable valve carrying said movable flue section and adapted to be moved to a position in which it is interposed between said inlet and outlet when said flue section is removed from its position between said inlet and outlet.

15 3. In valve apparatus, the combination of a casing having an inlet port and an outlet, a movable flue section forming a passageway between the inlet and outlet, a movable valve carrying said movable flue section and adapted to be moved to a position in which it is interposed between said inlet and outlet when said flue section is removed from its position between said inlet and outlet, and means engaging said valve for moving

20 the latter and said movable flue section together.

4. In valve apparatus, the combination of a casing having an inlet port and an outlet, a movable flue section forming a passageway between the inlet and outlet, a movable valve carrying said movable flue section and adapted to be moved to a position in which it is interposed between said inlet and outlet when said flue section is removed from its position between said inlet and outlet, and

counter-weighted lever mechanism extending into said casing and engaging said valve, for the purpose set forth.

5. In valve apparatus, the combination of a casing having an inlet port and an outlet, a movable flue section forming a passageway between the inlet and outlet, a movable valve carrying said movable flue section and adapted to be moved to a position in which it is interposed between said inlet and outlet when said flue section is removed from its position between said inlet and outlet, and means affording an interlock between said valve and movable flue section in one position of the latter, said flue section being shiftable on said valve into a position in which it is out of interlocking position relative to said valve, permitting said flue section to be lifted from said valve.

6. In valve apparatus, the combination of a casing having an inlet port and an outlet, a movable flue section forming a passageway between the inlet and outlet, a movable valve carrying said movable flue section and adapted to be moved to a position in which it is interposed between said inlet and outlet when said flue section is removed from its position between said inlet and outlet, and means affording an interlock between said valve and movable flue section in one position of the latter, said flue section being shiftable on said valve into a position in which it is out of interlocking position relative to said valve, permitting said flue section to be lifted from said valve, the upper part of said casing being removable and when removed permitting of the lateral movement of said movable flue section on said valve for disconnecting these parts.

JOHN LEVEY.
